(57) **CLAIM**

The ornamental design for a drug delivery device, as shown and described.

DESCRIPTION

1.1 is a front left perspective view;
1.2 is a front right perspective view;
1.3 is a front perspective view with a portion of the device rotated;
1.4 is a front left perspective view with a portion of the device rotated;
1.5 is a front right perspective view with a portion of the device rotated;
1.6 is a front perspective view;
2.1 is a front left perspective view;
2.2 is a front right perspective view;
2.3 is a front perspective view with a portion of the device rotated;
2.4 is a front left perspective view with a portion of the device rotated;
2.5 is a front right perspective view with a portion of the device rotated; and
2.6 is a front perspective view.

The broken lines depict portions of the drug delivery device that form no part of the claim.

1 Claim, 12 Drawing Sheets
